TEXTILE MACHINERY

Alfons Jasicek, Vienna, Austria, and
Fritz Polnauer, Berlin, GermanyOriginal application May 9, 1931, Serial No.
536,264. Divided and this application June 3,
1935, Serial No. 24,720. In Germany April 3,
1929

1 Claim. (Cl. 139—13)

Our invention relates to textile machinery, and more particularly to circular looms of the type in which the thread bearing member, for instance a shuttle, is driven by electromagnetic forces.

As in our prior application, Ser. No. 536,264, filed May 9, 1931, of which this case is a division, the object of our present invention is to eliminate the drawbacks of electric propulsion as designed heretofore for circular looms, in which the shuttle constituted an armature of a rotating magnet acting upon the same at one side of the shed, and another magnet was provided at the opposite side of shed and propelled by the magnetic reaction between itself and the shuttle.

Another object of our invention is to provide means including a fixed magnet system with a circular gap for generating a travelling electric field, and a shuttle or shuttles having a part of conducting and non-magnetizable material for engaging said gap.

20 A further object of our invention is to provide a set of radial droppers intermediate the warp threads defining the circular gap.

The part of the shuttle which engages the gap may be shaped in various ways. It may be a flat fin or a slotted tube, for instance. There may also be two gaps and the gap-engaging member may be U-shaped or looped for engaging them.

In the accompanying drawing various embodiments of our invention are illustrated diagrammatically by way of example.

In the drawing:

Figs. 1, 4 and 6 show plan views of different forms of the magnet system of the loom.

35 Figs. 2 and 5 show elevations of the magnet system and the shuttle, and

Fig. 3 shows the winding of the magnet system.

Referring to Figs. 1, 2, 3 and 5 the magnet system consists of an inner circular magnet E pro-

vided with a winding W, of an outer iron ring Er for closing the magnetic force lines, and of radial droppers 57, 58 extending through a portion of the space between the magnet and the ring to leave a gap 67 for the fin f of the shuttle S. The winding W of the magnet or stator is fed with alternating or three-phase current, and in consequence thereof a wandering magnetic field is produced the force lines of which go through the fin f of the shuttle S, generating therein rotary currents and imparting a circular movement to the shuttle along the gap 67. The droppers 57, 58 serve for closing the magnetic force lines of the stator E across the ring Er, and also for guiding the warp threads T (Figs. 2 and 5). Dovetailed rings 63, 64 of non-magnetizable material are secured to the ring Er for holding the droppers 57, and similar rings 65, 66 are provided for securing the droppers 58 to the magnet E. Preferably a layer of insulating material is inserted between these rings 64—66 and the part supporting them. Between the droppers distance holders 59 and 60 are inserted and the free ends of the droppers are held by braces 61.

In Fig. 4 the positions of the magnet E and of the ring Er are interchanged, while in Fig. 6 the magnet E and ring Er are replaced by two magnets E₁ and E₂, both provided with windings W.

What we claim is:

In a circular loom, two sets of radial droppers radially spaced to form a circular gap, the individual droppers being circumferentially spaced to provide slots for the warp threads, a fixed magnet system connected to said droppers for generating a traveling electric field, and a shuttle having a part of conducting and non-magnetic material engaging said gap.

ALFONS JASICEK.
FRITZ POLNAUER.
